UNITED STATES PATENT OFFICE.

CARL RUDOLF BERGMANN, OF BERLIN, GERMANY.

MACHINE FOR MANUFACTURING ENVELOPS, PAPER BAGS, OR THE LIKE.

SPECIFICATION forming part of Letters Patent No. 746,917, dated December 15, 1903.

Application filed September 22, 1902. Serial No. 124,427. (No model.)

To all whom it may concern:

Be it known that I, CARL RUDOLF BERGMANN, envelop manufacturer, a subject of the Emperor of Germany, and a resident of Alexanderstrasse 93 and 94, Berlin, in the Empire of Germany, have invented certain new and useful Improvements in Machines for Manufacturing Envelops, Paper Bags, or the Like, of which the following is a specification.

10 In machines for the manufacture of envelopes, paper bags, and the like up to the present in use it is customary when the size of the envelopes, &c., has to be varied to interchange either the whole folding apparatus or

15 to make the folding-plates divided and interchangeable with each other. In the first case the cost of an envelop-machine is very high, as the folding apparatus represents the most expensive part of the machine, and in the

20 other case, where the folding-plates are divided and both parts interchangeable, the envelopes or paper bags remain unpressed at the point between the two folding-plate parts, so that all the envelopes or paper bags have

25 to be again specially pressed.

The object of the present invention is to remove the disadvantages existing in the known contrivances. This is accomplished by making each folding-plate in two parts—that is, 30 by a hinge or joint which serves at the same time as a support and a special plate connected with said hinge or joint, said plate being undivided in the direction of the edge of the envelop or paper bag. The separate 35 plates can therefore be disconnected, the folding apparatus adjusted in a suitable manner, and smaller or larger plates fixed if the size or shape of the envelopes or paper bags has to be varied. This improvement can, however,

40 also be applied with advantage to machines when the folding-plates were up to the present made divided in the direction of the edge of the envelop.

The drawings represent the upper part of 45 such a machine, Figure 1 being a longitudinal section on line A B of Fig. 2; Fig. 2, a plan view. Fig. 3 is a plan view of the machine, provided, however, with smaller plates. Fig. 4 shows the application of the present 50 improvement to machines having the folding-plates divided in the direction of the en-

velop edge. Figs. 5 to 7 are detail views. Fig. 8 represents the arrangement of plates for the envelop shown, for example, in Fig. 9.

The machine-frame 10 is provided at its upper part with an opening 11, over which the folding apparatus is placed. The latter is arranged on four blocks 12, 13, 14, and 15, of which 12 is fixed firmly on the frame-plate 17, while the other three are movable. All 55 the blocks can be moved to or from each other by means of suitable guide-rails 16, Fig. 5. On each of these blocks is a hinge 18, which is connected with the adjacent block by means of a guiding-slot 20. Each 60 hinge-joint carries one of the four angle-plates 19, extending upward and adjustable with the blocks, also having connection with one another by guiding-slots 21, and is shown, for example, in Fig. 6 serving as a guide to 65 the envelop-sheet passing to the folding apparatus. Each hinge is detachably connected with a plate 22, corresponding in size and shape to the flaps of the envelop, paper bag, and the like to be made. These plates 22 70 have, however, to be arranged in such a manner that they have contact at all points with the interchangeable base-plate 24, arranged on an oscillating foundation 23. The oscillating movement given to the plates 22, with 75 the corresponding hinge, takes place in the ordinary way by means of connecting-rods 25, cranks 26, and suitable lever mechanism 27 28 29 30 by cams and step-pulleys 31 32 33 34, the cam 31 acting on angle-lever 27, cam 80 32 on lever 28, cam 33 on lever 29, and, finally, cam 34 on driving-rod 30. The oscillating plate 23 is actuated by a cam 36 by means of an oscillating double lever 35. All the cams can be placed on a common shaft 37. 85

The operation is as follows: If the cams 31 to 34 are caused to assume such a position that all the plates 22 are vertical, as indicated in dotted lines in Fig. 7, and the plate 23 is in the position shown in Fig. 1, then a sheet 95 of paper cut to the correct size and placed on the frame formed by angle-plates 19 will be moved downward, by means of the stamp 38 (shown in dotted lines in Fig. 1,) onto the base-plate 24. At the same time the projecting edges of the paper are bent over to about half the complete fold. On the stamp 38 re-

turning, the folding-plates come into operation and bend each flap of the envelop or paper bag over and fold them to a sharp edge. The rising-and-falling movement of stamp 38 can be effected by a cam 39 and convenient lever connections 40 41 and rods 42. When the envelop or paper bag is folded, the folding-plates move again to a vertical position, and at the same time a downward movement of plate 23 into the position shown in dotted lines in Fig. 1 takes place, so that the envelop can slide into the box or drawer 43 below. If, for example, smaller envelopes or paper bags are to be made with the same machine, the connection between hinges 18 and the plates 22 is unfastened. The latter are removed, the slot-guides 20 21 and the cranks 26 concerned disconnected and, finally, the connections 44 45 of angle-lever 27 and rod 30. After this operation the blocks 13, 14, and 15, with the parts connected thereto, are moved both toward one another and toward the block 12 and the connections remade. The shortening of rod 30 on one hand and the adjustment of joint 46, connected with angle-lever 27, is necessary, as otherwise the movement of the folding-plates belonging thereto would be altered. When displacing the folding apparatus and interchanging plates 22, base-plates 24 must of course also be interchanged, as otherwise a displacement of the blocks and the whole apparatus would not be possible.

Fig. 7 shows in solid lines the folding-plate 35 in folded-down position, while the dotted lines show it raised.

If envelops, for example, as shown in Fig. 9, are to be made, it is necessary that the folding-plates should not be folded down together, 40 but one after the other, according to the position of the envelop-flaps *a b c d*—that is to say, plate folding the flap *a* must be moved down first and the plates folding the envelop *b d* last.

45 As shown in Fig. 4, each hinge consists of

two parts 18 18'. One part of each is fixed to blocks 12, 13, 14, or 15, and both these parts are connected to one of the interchangeable plates 22.

For sake of clearness of illustration the upper angle-plates 19 are omitted in Figs. 2 to 4 and 8.

It is immaterial in what manner separate details are constructed, and the driving mechanism used is of secondary importance. The 55 interchangeable plates 22 may also be of any convenient shape, as will be seen in Figs. 2 to 4. The shape of the folding-plates is always also guided by the shape of the envelop, paper bag, and the like to be made. For example, one or more folding-plates can be made perforated or as is the case with one of the plates in Fig. 8, provided with bars 48 for effecting the folding over of the envelop-flaps. 65

Having thus described my invention, the following is what I claim as new therein and desire to secure by Letters Patent:

1. In a machine for manufacturing envelops of different sizes, means for folding the 70 envelop comprising a plurality of hinges adjustable toward and from each other, and a plurality of interchangeable folding-plates corresponding to the shape of the envelop-flaps, secured to said hinges. 75

2. In a machine for manufacturing envelops of different sizes, means for folding the envelop comprising a plurality of hinges adjustable toward and from each other, a plurality of interchangeable folding-plates corresponding to the shape of the envelop-flaps, secured to said hinges, and an interchangeable bed-plate corresponding to the shape of the envelop to be made. 80

In witness whereof I have hereunto set my 85 hand in presence of two witnesses.

CARL RUDOLF BERGMANN.
